Nelson McDonald

UNITED STATES PATENT OFFICE.

WILLIAM HUBBARD, OF ROCHESTER, NEW YORK, ASSIGNOR TO UNITED SHOE MANUFACTURING CORPORATION, OF PATERSON, NEW JERSEY, A CORPORATION OF NEW JERSEY.

MACHINE FOR FINISHING HEELS.

1,273,063.

Specification of Letters Patent.

Patented July 16, 1918.

Original application filed October 17, 1916, Serial No. 126,198. Divided and this application filed March 13, 1918. Serial No. 222,131.

To all whom it may concern:

Be it known that I, WILLIAM HUBBARD, a citizen of the United States, residing at Rochester, in the county of Monroe and State of New York, have invented certain Improvements in Machines for Finishing Heels, of which the following description, in connection with the accompanying drawings, is a specification, like reference characters on the drawings indicating like parts in the several figures.

This invention relates to a machine for cleaning the edge of an ornamental heel lift.

In my co-pending application Serial No. 126,198, filed October 17, 1916, of which this application is a division, there is described a method of finishing a heel having an ornamental lift of metal, celluloid or similar material which comprises treating the lateral surface of the heel, including the edge of the ornamental lift, in the usual manner and then cleaning the edge of the ornamental lift to produce on the heel an ornamental stripe of contrasting color.

According to one feature of the present invention there is provided a cleaning tool the width of the operative face of which is not greater than the width of the edge of the ornamental lift, and a rest for the tread face of the heel constructed and arranged to maintain the edge of the lift in contact with the tool as the heel is turned to subject the edge of the lift to the cleaning action of the tool said rest and tool being relatively adjustable.

In the illustrative machine several adjustments are possible so as to provide for heels of different shapes and for different locations of the ornamental lift with respect to the tread face of the heel.

These and other features of the invention, including certain details of construction and combinations of parts, will be described as embodied in an illustrative machine and pointed out in the appended claims.

Referring to the accompanying drawings,—

Figure 1 is a perspective of a portion of a heel burnishing machine in which the present invention is embodied, and

Fig. 2 is a perspective showing a Louis

heel in process of having the edge of the ornamental lift cleaned.

The heels, to the finishing of which the present invention is directed, comprise a body portion which may be of the usual leather-lifts and an ornamental lift of some material such, for example, as aluminum the bright edge of which is designed to produce a stripe of color contrasting with the color of the body of the heel. Commonly this ornamental lift is placed just above the top lift. In finishing a heel of this kind the lateral surface is coated with coloring matter or wax or both as may be desired, and the coating smoothed and burnished. When this has been accomplished, the original color of the edge of the ornamental lift has been dulled or obscured; and it becomes necessary to clean from the edge of the ornamental lift the coating.

In Fig. 1 there is shown a portion of a heel burnishing machine which has been fitted with means for cleaning the edge of the ornamental lift. This machine is in general of a well known form and will not be described in detail. It is provided with the usual iron 13 the function of which is to apply to the heel a coating of hot wax, with a smooth roll 15 to which the heel is next presented, and with a polishing brush 17 by which the wax is brushed in and polished.

Fast to the end of the rotary shaft 19 which carries the roll 15 and brush 17 is a wheel 21 the operative edge of which has substantially the same width as that of the ornamental lift, this edge comprising small teeth which rapidly remove the coloring matter and wax. In order to assist in the presentation of the heel to the cleaning wheel 21 a tread-rest 23 in the form of a plate is fastened at one end to a screw bolt 25, said bolt passing through ears on a bracket or support 27 and having at its inner end a square head which bears against a flat surface on the bracket and thereby prevents the bolt from turning. A thumb nut 28 provides means for moving the bolt, and with it the tread-rest, in and out. The bracket 27 is mounted on a carrier comprising a pin 29 having at its outer end an eye, through which passes the stem of a bolt 30.

which is threaded into said bracket, the bracket thus being angularly adjustable about the axis of the bolt 30. The pin is adjustably held in a socket in one end of a member 31, the other end of which is adjustably fastened to one end of an arm 33 by a screw, the head or handle of which is indicated at 35. The hub at the end of the arm 33 is split and is adjustably fastened to a stationary rod 37 by a pinch-screw. The tread-rest may thus be adjusted in a path parallel to the axis of the bolt 25, angularly about the axis of the bolt 30, in a path parallel to the axis of the pin 29, and angularly about either the axis of the screw 35 or that of the rod 37. By these adjustments it is possible to provide for heels of different shapes and for top lifts of different thickness.

20 The heel is first inked and blacked if the finished heel is to be given a black finish. It is then presented to the iron 13 and swung around until a coating of wax is applied to the whole lateral surface thereof.

25 The waxed heel is then similarly presented to the smoothing roll 15 and thereafter to the brush 17. At this stage the lateral surface of the heel is covered with an opaque and burnished coat which obscures the edge 30 of the ornamental lift. The heel is then presented to the cleaning wheel 21 in the manner shown in Fig. 2 and swung around so as to remove the coloring matter and wax from the edge of the lift progressively 35 beginning at a point in the junction of the lateral surface with the breast at one side of the heel and ending with a similar point at the other side of the heel. This ordinarily completes the treatment of the heel, 40 but in some cases it is desirable to rub the cleaned edge of the lift and the adjacent coat of finishing material to remove the dust or chips and to polish the edge of the lift. When this further step is desirable, 45 the heel is presented again to the roll 15 or brush 17 or to both.

The tread part 23, it should be noted, is capable of various adjustments to provide for various shapes of heels and for various 50 locations of ornamental lifts. In Fig. 2 a Louis heel is shown, in which the edge of the ornamental lift is beveled, and consequently the tread rest is inclined to the plane of rotation of the tool 21. This inclination may be varied by adjusting the rest about the axis of the bolt 30 to provide for a lift having a different bevel on its edge; and, if this adjustment does not secure the desired relation between the rest and the 60 tool, the nut 28 may be manipulated, or the rest may be moved in the direction of the axis of the pin 29 or about said axis, which is approximately parallel to that of the shaft 19. If this combination is not sufficient, the screw 35 may be loosened and the

rest raised or lowered by swinging it about the axis of the screw. And finally, if desirable, the arm 33 may be adjusted about the rod 37.

The heel, which has been referred to above, forms the subject-matter of a co-pending application Serial No. 111,739, filed July 27, 1916.

Having thus described my invention, what I claim as new and desire to secure by Letters Patent of the United States is:

1. A machine for cleaning the edge of an ornamental lift in a heel, having, in combination, a cleaning tool the width of the operative face of which is substantially equal 80 to that of the edge of the lift, a rest for the tread face of the heel constructed and arranged to maintain the edge of the lift in contact with the tool as the heel is turned, means for producing relative adjustment 85 between the tool and the rest to provide for differently located lifts and means for operating the tool.

2. A machine for cleaning the beveled edge of an ornamental lift in a heel, having, in combination, a cleaning tool the width of the operative face of which is not greater than that of the edge of the lift, a tread rest for the heel, and means for producing relative angular adjustment between 90 the tool and rest to cause the tool to clean the beveled edge of the lift and to provide 95 for lifts having edges beveled on different angles.

3. A machine for cleaning the edge of an 100 ornamental lift in a heel, having, in combination, a rotary tool having a narrow face of a width not greater than that of the edge 105 of the lift, and a tread rest for the heel, the supporting face of the rest being inclined to the plane of rotation of the tool.

4. A machine for cleaning the edge of an ornamental lift in a heel, having, in combination, a rotary tool having a narrow face of a width not greater than that of the edge 110 of the lift, a tread rest for the heel, the supporting face of the rest being inclined to the plane of rotation of the tool, and means whereby the rest may be adjusted to vary its angle of inclination.

5. A machine for cleaning the edge of an ornamental lift in a heel, having, in combination, a rotary tool having a narrow face of a width not greater than that of the edge 115 of the lift, a tread rest for the heel, the supporting face of the rest being inclined to the plane of rotation of the tool, and means whereby the rest may be adjusted toward and from the tool.

6. A machine for cleaning the edge of an 125 ornamental lift in a heel, having, in combination, a rotary tool having a narrow face of a width not greater than that of the edge of the lift, a carrier adjustable angularly toward and from the tool, a support 130

mounted on the carrier and angularly adjustable with respect thereto, and a tread rest adjustably mounted on the support.

7. A machine for cleaning the edge of an ornamental lift in a heel, having, in combination, a rotary tool having a narrow face of a width not greater than that of the edge of the lift, a carrier adjustable in a path approximately parallel to the axis of the

tool and angularly toward and from the tool, a support mounted on the carrier and angularly adjustable with respect thereto, and a tread rest adjustably mounted on the support.

In testimony whereof I have signed my name to this specification.

WILLIAM HUBBARD.
